Des. 197,371
Patented Jan. 21, 1964

197,371

BUILDING FOR RESTAURANTS AND THE LIKE

James A. Anderson, 1021 McEvers Road,
Memphis, Tenn.

Filed July 17, 1963, Ser. No. 75,845

Term of patent 7 years

(Cl. D13—1)

FIG. 1 is a top plan view of building.
FIG. 2 is the front elevation embodying my new design, sides and rear being substantially the same.

I claim:

The ornamental design for a building for restaurants and the like, substantially as shown and described.
